UNITED STATES PATENT OFFICE.

JOHN J. GARD, OF HARVEY, ILLINOIS, ASSIGNOR TO BUDA FOUNDRY & MANUFACTURING COMPANY, OF CHICAGO, ILLINOIS, A CORPORATION OF ILLINOIS.

CROSSING-GATE.

No. 876,166.

Specification of Letters Patent.

Patented Jan. 7, 1908.

Application filed January 25, 1907. Serial No. 353,990.

To all whom it may concern:

Be it known that I, JOHN J. GARD, a citizen of the United States, residing at Harvey, in the county of Cook and State of Illinois, have invented certain new and useful Improvements in Crossing-Gates, of which the following is a specification.

My invention relates to crossing gates and particularly to the mechanism for operating and locking them in position. The invention has for its objects: to provide a mechanism of this character of greater simplicity and positiveness of operation than has been secured in the devices now in use; to provide a device in which the operating mechanism is securely locked in its extreme positions; and to provide an arrangement of parts whereby the locking mechanism is automatically moved to position by engagement 20 with the gate operating means. These and other objects are attained by my invention, one embodiment of which is illustrated in the accompanying drawing wherein,

Figure 1 is a longitudinal section through the operating mechanism, the gate being shown in lowered position,

Figure 2 is a section similar to that of Figure 1 but with the operating parts in the position assumed when the gate is raised,

Figure 3 is a section through the casing on the line III—III of Figure 1, looking to the right, the operating parts being in elevation, and

Figure 4 is a section through the casing on the line III—III of Figure 1 looking to the left, the operating parts being in elevation.

Referring now to the drawings and particularly to Figures 1 and 2, 1 is the casing of the device, 2 is the gate itself mounted upon 40 the shaft 3, and provided with the usual counterweight 4, 5 is the operating cylinder, 6 is the piston of such operating cylinder, 7 is a connecting rod, 8 is the operating arm which is secured rigidly to the shaft 3, 9 is 45 the locking arm for holding the gate in its two extreme positions and 10 is the weight for giving the locking arm its final movement to locking position. The connecting arm 7 has an enlargement provided with the slot 12 intermediate its ends, and is connected at 50 its lower end to the piston rod 6 by means of the pivot 8' while its upper end is provided with a longitudinal slot 10' for coöoperating with the pivot 11 carried by the operating 55 arm 8. The operating arm 8 is made in the

form of an open triangle and is provided at each of its ends with a locking recess 14. The locking arm 9 is in the form of a bell crank lever and carries at one end a pin 13 adapted to engage the sides of the slot 12, and at the other end the locking rod 16 adapted to engage the locking recesses 14 in the ends of the operating arm 8. The weight 10 constitutes the means for moving the locking arm 9 to its extreme position with the locking rod 16 in engagement with one of the recesses 14, and is connected to the locking rod 16 by means of the chain 18. The locking arm 9 is pivotally supported by means of the trunnion 17, which trunnion extends transversely 70 across the casing and is provided with an off-set portion 19, to receive the chain 18, when the locking arm is moved to the position shown in Figure 2. Fluid is admitted to the operating cylinder 5 by means of the 75 pipes 20 and 21.

Starting with the device in the position shown in Figure 1, the operation is as follows. Fluid being admitted to the cylinder 5, the piston rod 6 descends and as the pin 13 is in 80 immediate contact with the upper side of the slot 12 the bell crank lever 9 will first be operated thereby releasing the locking rod 16 from the locking recess 14 in the arm 8. This release occurs before any movement of 85 the arm 8 because of the slot 10' which permits of a downward movement of the connecting rod 7 before the upper side of such slot engages the pivot 11. A further movement of the connecting rod rotates the operating arm 8 thereby raising the gate, which motion is continued until the parts approach the position shown in Figure 2. After the arm of the bell crank lever 9 which carries the locking rod 16 has passed its vertical position 90 the weight 9 will carry the locking rod 16 to the position shown in Figure 2 and also bring the cross rod 13 on the other arm of such bell crank lever to the bottom of the slot 12 as indicated in Figure 2. It will be seen that the 100 engagement of the locking rod 16 with the locking recess 14 prevents any rotary movement of the arm 8 and securely locks such arm in position. When it is desired to lower the gate the operation is reversed and air is admitted to the under side of the piston thereby raising the connecting rod 7. The first part of this movement of the connecting rod operates the locking member 9 for the reason that the pin 13 is in engagement with the lower edge 110

of the slot 12 at the beginning of the movement of the connecting rod, and as the pivot 11 engages the top of the slot 10 in the position of Figure 2, the locking device is completely free before the connecting rod commences to operate the arm 8. A still further movement of the connecting rod rotates the arm 8 and brings the parts finally to the position of Figure 1, the bell crank lever locking member 10 moving to its final position with its locking rod 16 in engagement with the locking recess 14 and with its pin 13 in engagement with the upper part of the slot 12 by virtue of the weight 9 which moves the bell crank lever 15 independently of the connecting rod after the right hand end of such bell crank lever has passed its vertical center line. It will be seen from the foregoing that the operating mechanism involved is of a very simple nature and that the gate is locked securely in its two extreme positions by a mechanism independent of the operating mechanism. It will also be seen that by reason of the two sets of lost motion connections, the locking 25 devices are free before the operating mechanism commences to operate the arm 8 thus rendering the part easy of operation. It will also be apparent that in the operation of the device the operating mechanism for the gate 30 gives the locking means a preliminary movement while the weight 9 gives such locking mechanism its final movement to locking position so that in any case the lock-parts will engage tightly at the end of their travel 35 irrespective of the wear of the operating parts.

Having thus described my invention and illustrated its use, what I claim as new and desire to secure by Letters Patent, is the following:

1. In combination, a gate operating shaft, an operating arm secured thereto and provided with a pair of locking recesses, means for operating the operating arm, and an oscillatory locking arm having connection to the operating means and adapted to engage one of the locking recesses when the operating and locking arms reach either of their two extreme positions.
2. In combination, a gate operating shaft, an operating member secured thereto and provided with lock engaging means, lost motion connections for operating the operating member, and a locking member having a lost motion connection with said operating means and adapted to move the lock engaging means partially to locking position, and a weight for giving the locking member its final movement to locking position.
3. In combination, a gate operating shaft, an operating member secured thereto and provided with lock engaging means, lost mo-

tion connections for operating the operating member, and a locking member having a lost motion connection with said operating means and adapted to move the lock engaging means partially to locking position, and independent means for giving the locking member its final movement to locking position.

4. In combination, a gate operating shaft, an operating arm secured thereto and provided with a pair of locking recesses, a locking arm adapted in one extreme position to engage one of said recesses and in the other extreme position to engage the other of said recesses and an operating means connected to the operating arm and the locking arm and adapted to cause the engagement of the locking arm with one of the said recesses when the operating arm reaches one of its extreme positions.

5. In combination, a gate operating shaft, an operating arm secured thereto and provided with a pair of locking recesses, a locking arm adapted in one extreme position to engage one of said recesses and in the other extreme position to engage the other of said recesses and an operating means connected to the operating arm by a lost motion connection and to the locking arm, whereby the locking arm is released from its locking connection with the recesses before the operating means commences to turn the operating arm.

6. In combination, a gate operating shaft 3, an operating arm 8 secured thereto and provided with the two locking recesses 14, an oscillatory locking arm 9 provided with engaging means 13 and 16, a weight 10 for carrying the arm 9 to its final locking position and an operating member 7 provided with the slot 10' for engaging the end of the arm 8 and the slot 12 for engaging the engaging means 13.

7. In combination, a gate operating shaft, an operating member having operative connection with the shaft and provided with lock engaging means, power means for operating the operating member secured thereto by lost motion connections, and a locking member having connection with the power means for securing a preliminary locking movement of the locking member, and independent automatic means for giving the locking member its final movement to locking position and holding it in such position.

In testimony whereof, I hereunto sign my name in the presence of the two subscribed witnesses.

JOHN J. GARD.
